DESIGN FOR A CHAIR

Harry W. Kranz, Lakewood, Ohio, assignor to The Cleveland Welding Company, Cleveland, Ohio,
a corporation of Ohio

Application October 23, 1939, Serial No. 87,812

Term of patent 3½ years

To all whom it may concern:

Be it known that I, Harry W. Kranz, a citizen of the United States and a resident of Lakewood, county of Cuyahoga, and State of Ohio, have invented a new, original, and ornamental Design for a Chair, of which the following is a specification, reference being had to the accompanying drawing, forming a part thereof.

In said annexed drawing:

Fig. 1 is a perspective view of a chair showing my new design; and Fig. 2 is a top perspective view thereof.

Fig. 3 is a sectional view of the chair back taken along the line 3—3 on Fig. 1; and Fig. 4 is a sectional view of the chair back taken along the line 4—4 on Fig. 1.

I claim:

The ornamental design for a chair, as shown,

HARRY W. KRANZ.
